[57] ABSTRACT

The anti-bacterial agents of this invention present the following structural formula:

in which

R¹ is a member selected from the group consisting of —H, alkyl of 1 to 6 carbon atoms and aryl of 6 to 8 carbon atoms;

R² is a member selected from the group consisting of —H, alkanoyloxy of 2 to 6 carbon atoms,

and when taken the 3-carboxyl group,

M is a member selected from the group consisting of

—H, an alkali metal and —NH₄;

m is one of the integers 0—2;

n is one of the integers 2—4; and

the pharmaceutically acceptable hydrohalide acid addition salts thereof.

7-[2-(CYCLOALKYLENEIMINO-2YL)THI-OACETAMIDO]CEPHALOSPORANIC ACID

DESCRIPTION OF THE INVENTION

In accordance with this invention there is provided anti-bacterial agents of the formula:

in which

R¹ is a member selected from the group consisting of —H, alkyl of 1 to 6 carbon atoms and aryl of 6 to 8 carbon atoms;

R² is a member selected from the group consisting of —H, alkanoyloxy of 2 to 6 carbon atoms,

and when taken with the 3-carboxyl group,

M is a member selected from the group consisting of —H, an alkali metal and —NH₄;

m is one of the integers 0-2;

n is one of the integers 2-4; and

the pharmaceutically acceptable hydrohalide acid addition salts thereof.

The term "alkyl," as it is used herein, is intended to embrace univalent aliphatic hydrocarbons containing the indicated number of carbon atoms, representative of which are the methyl, ethyl, propyl, i-propyl, butyl, i-butyl, amyl and hexyl radicals. The term "aryl" is in-

tended to embrace univalent aromatic hydrocarbons containing 6 to 8 carbon atoms such as, phenyl, tolyl, ethylphenyl and di-methylphenyl. The term "alkanoyloxy" is intended to embrace the unsubstituted lower aliphatic carboxy radicals such as acetoxy, propionyloxy, butyryloxy, pentanoyloxy and hexanoyloxy radicals.

The compounds of this invention are prepared by reacting an azacycloalkyl-2-thione with an appropriately substituted 7- ω (haloalkanoylamido)cephalosporin derivative, thusly

35 in which the values of R¹, R², M, n and m are given above and HX represents the hydrohalide addition salt, the halide being that of the haloalkanoylamido cephalosporanic acid derivative employed as a reactant. Preferably, X is —Cl or —Br.

40 The preferred group of compounds, from the standpoint of availability of reactants, ease of reaction and general production economics, are those of the formula:

in which

60 R¹ is a member selected from the group consisting of —H, alkyl of 1 to 6 carbon atoms and phenyl;

R² is a member selected from the group consisting of

—H and acetoxy;

n is 2, 3 or 4; and

X is —Cl or —Br.

The compounds of this invention are active anti-bacterial agents, effective against gram-positive and gram-negative bacteria and resistant staphylococcus. The ac-

tivity of the compounds was established by using the well known, scientifically accepted agar serial dilution testing technique whereby specific bacterial strains are grown for 18 hours in brain heart infusion at 35°C. Prior to use, the cultures are diluted 10-1 with the infusion. Stock concentrations of the anti-bacterial agent are prepared (2.500 ug per milliliter) in a suitable vehicle. Two-fold dilutions are made with sterile distilled water appropriately buffered. One milliliter quantities of each dilution are incorporated in 9 milliliter Seed 10 agar in sterile Petri plates. The hardened surface is inoculated with the test bacterium using a Steers replicating device. The plates are incubated for 18 hours at 35°C. The least amount of anti-bacterial compound that completely inhibits the test organism is the minimum inhibitory concentration (MIC) expressed in micrograms per milliliter.

Hence, the compounds of this invention are useful in the fields of comparative pharmacology and microbiology and for the control and comparative analysis of bacterial colonies. The compounds are to be used to inhibit the growth of bacteria in the conventional manner and by the known methods of utilizing cephalosporin derivatives.

The following examples illustrate the preparation of representative cephalosporin derivatives of this invention. The compounds produced in the following examples are generally recovered in the hydrohalide addition salt form, frequently with a small amount of solvent, the latter being readily removed by further vacuum stripping of the product. The free bases are readily formed by neutralization of the hydrohalide by conventional techniques. The activity of each exemplified product is presented for those specific bacterial strains against which the compound exemplified was active at or below 250 micrograms per milliliter. The representative nature of the bacterial strains employed to demonstrate anti-bacterial activity are indicative of the broader applicability of the compounds of this invention in the control of bacterial infestations other than those specifically referred to in each of the following examples. The bacteria are named, followed by the specific strain and the concentration in micrograms per milliliter at which 100 percent inhibition occurred. The abbreviations for each bacterium are:

BA SU	Bacillus subtilis
ST AU	Staphylococcus aureus
HE SP	Herella species
NE CA	Neisseria catarrhalis
EN AE	Enterobacter aerogenes
ES CO	Escherichia coli
ES IN	Escherichia intermedia
SA PA	Salmonella paratyphi
KL PN	Klebsiella pneumoniae
BO BR	Bordetella bronchiseptica
PR VU	Proteus vulgaris

EXAMPLE I

7-[2-(4,5,6,7-Tetrahydro-3H-azepin-2-ylthio)acetamido]cephalosporanic acid.

7-[2-Bromoacetamido]cephalosporanic acid (0.78 gram, 2 millimole) and ω -thioproline (0.26 gram, 2 millimole) were dissolved in acetone and the acetone solution was stirred at room temperature for 4 hours. After filtering off some insoluble material the solution was taken to dryness at a temperature below 30°C. The residual solid (1.0 gram) was triturated with diethyl ether and collected.

Elemental Analysis for $C_{18}H_{23}N_3O_6S_2 \cdot HBr \cdot \frac{1}{2}(C_2H_5)_2O$:

Calc'd: C, 42.93; H, 5.22; N, 7.50. Found: C, 43.02; H, 4.71; N, 7.13.

EXAMPLE IV

7-[2-Phenyl-2-(4,5,6,7-tetrahydro-3H-azepin-2-ylthio)acetamido]cephalosporanic acid.

The procedure of Example I was repeated with the exception that 7-[2-bromo-2-phenylacetamido]cephalosporanic acid was employed in lieu of 7-(2-

bromoacetamido)cephalosporanic acid.
